UNITED STATES PATENT OFFICE.

GEORGE GODDU, OF WINCHESTER, MASSACHUSETTS, ASSIGNOR TO UNITED SHOE MACHINERY COMPANY, OF PATERSON, NEW JERSEY, A CORPORATION OF NEW JERSEY.

EYELETING-MACHINE.

No. 874,669.

Specification of Letters Patent.

Patented Dec. 24, 1907.

Application filed March 27, 1907. Serial No. 364,803.

To all whom it may concern:

Be it known that I, GEORGE GODDU, a citizen of the United States, residing at Winchester, in the county of Middlesex and Commonwealth of Massachusetts, have invented 5 certain Improvements in Eyeletting - Machines, of which the following description, in connection with the accompanying drawings, is a specification, like reference characters on the drawings indicating like parts in the several figures.

This invention relates to eyeletting machines and pertains more particularly to the 15 type of machine known as the duplex eyeletting machine in which opposite sides of a shoe-upper are operated upon simultaneously.

In setting eyelets in shoe uppers it is usually the practice to set the lower eyelet on each flap with a somewhat greater "spread" than 20 the succeeding ones, that is, at a somewhat greater distance from the edge of the lacing-slit than the others, and thereafter the remaining eyelets are set at a lesser distance from the edge of the lacing-slit. In the machine disclosed in a co-pending application 25 for Letters Patent of the United States, Serial No. 153,822, filed April 22, 1903, means are provided whereby the operator may manually cause a spread of the lowest eyelets 30 greater than that of the succeeding ones. The upper is so presented to the machine that the eyelets at the bottom of the lacing-slit are set first and then the rest follow up the slit. In the machine of said application 35 when it is desired to set eyelets with a greater spread for the lowest eyelets, it is necessary for the operator to pull a lever before inserting each shoe-upper in the machine. This requires the constant attention of the operator 40 since if he fails to pull the lever at the proper time, the first eyelet in each flap is not set at the desired distance from the edge of the lacing-slit.

One of the objects of this invention therefore 45 is to provide automatic means whereby the lowest eyelets will be set with a spread greater than that of the succeeding eyelets.

One embodiment of this invention may be applied advantageously to an eyeletting machine which has a guide-plate and spring presser-feet on opposite sides thereof to hold 50 the two flaps of a shoe-upper in proper engagement with said guide-post. Such a machine is disclosed in a co-pending application 55 for Letters Patent of the United States, Se-

rial No. 329,722, filed August 8, 1906. In the machine of said application the guide-plate and the edge-gages secured thereto are moved in unison by the operator before he inserts the work in the machine. 60

The present invention contemplates the provision of means for moving the edge-gages automatically to vary the distance at which the eyelets will be set from the edge of the lacing-slit and in its broad aspect it is immaterial whether a guide-plate be moved at the same time or not. 65

In the preferred embodiment of this invention a slideable guide-plate having edge-gages secured thereto is held normally in rearward position relatively to an anvil-plate. While in this position it is evident that the shoe-upper which is in contact with said edge-gages will have its edges positioned rearwardly relatively to the anvil-plate and that the eyelets which are set at this time will be somewhat remote from the edge of the lacing-slit. After the first eyelet in each flap has been set the guide-plate and edge-gages carrying with them the shoe-upper are automatically moved forwardly to decrease the spread of the eyelets. The said parts are held in this forward position until the rest of the eyelets have been set. Upon the removal of the shoe-upper the guide-plate and the edge-gages are released and return to initial position. A convenient means for holding the guide-plate and attached edge-gages in their forward position and allowing them to be released when the stock is removed is as follows:—A ratchet which is secured to a stationary part of the machine is arranged to coöperate with a pawl carried by the slideable guide-plate. This pawl is so connected with relation to the spring presser-foot that when no stock is inserted between the guide-plate and presser-foot, said pawl will be out of engagement with the ratchet. When, however, the presser-foot is held away slightly from the guide-plate by the stock, the pawl engages the forwardly inclined teeth of the ratchet and retains the guide-plate and edge-gages in the forward position to which they are moved after the setting of the first eyelets, until the stock is removed. 100 A convenient arrangement for thus controlling the pawl by means of the spring presser-foot consists in connecting the two by means of a lever which holds the pawl out of engagement with the ratchet when the presser-foot 105 110

is not moved away from the guide-plate by the insertion of stock. When, however, the presser-foot is thus moved, the lever is moved out of operative relation with the pawl and a spring is allowed to force the pawl into contact with the ratchet. Means may be provided to prevent the backward movement of the guide-plate and edge-gages in case it should be desired to set all of the eyelets with the same uniform spread.

Referring to the accompanying drawings, which illustrate one embodiment of the invention,—Figure 1 is a top plan view showing the means for automatically varying the spread of the eyelets and the parts immediately associated with said means; Fig. 2 is a view in side elevation of a portion of the device; Fig. 3 is a fragmentary sectional view on the line *a*—*a*, Fig. 1, showing a device to lock the edge-gages in position to render the "spread" constant; Fig. 4 is a fragmentary sectional view on the line *b*—*b*, Fig. 1, showing a device for adjusting the amount of variation in the spread; Fig. 5 is a view similar to Fig. 1, showing the parts in the position which they assume after the first eyelet has been set and the stock has been fed; Fig. 6 is a view similar to Fig. 2 showing the parts in the position which they assume after the stock has been inserted; Fig. 7 is a view similar to Fig. 3 showing the locking device turned into disengaged position, and Fig. 8 is a view similar to Fig. 4 showing the adjusting device in position for making a change in the adjustment.

A feed-frame 1 which carries an anvil-plate 2 is pivotally supported on a stud 4 carried by an elbow-lever 6 which is pivoted at 8. The anvil-plate is provided preferably on two opposite sides with punching-blocks 10 and setting-dies 12. The arrangement is such that after the stock has been punched on the punching-blocks 10 the lever 6 is rocked so as to move the anvil-plate rearwardly and bring the setting-dies 12 into the position previously occupied by the punching-blocks as shown in Fig. 1. The feed-frame 1 is connected by means of links 14 and 16 to a lever 18 which is pivoted at 20. At the pivotal point 21 of the links 14 and 16 is pivoted a link 22 which in turn is pivoted at 24 to a fixed portion of the frame. The lever 18 is also connected by links 26 and 28 to a stud 30. This stud is clamped firmly to the link 28 by a binding-screw 32 and extends a short distance upwardly from said link. To the upper end of the stud a plate 34 is secured above which is a finger 36 on the stud 30, and rotatable thereon for adjustment when the pin now to be described is retracted. One end of this finger has a casing 38 within which is mounted a spring-pressed pin 40 having a head 42, the point of the pin being normally urged downwardly so as to be engaged in any one of a series of

holes 44 in the plate 34. The finger is thus adjustably mounted relatively to the plate. The other end of the finger has a reduced portion 46 for engaging a lug 48 on a guide-plate 49. Upon this guide-plate is a block 50 extending around three sides thereof but secured thereto by a screw 52. On opposite sides of the guide-plate, presser-feet 54 are secured to the block 50 by leaf-springs 56 which extend between pins 58 on the presser-feet for retaining the latter in alignment with said springs. The forward end of the block surrounds the guide-plate and forms edge-gages 60 to determine the position of the stock. The guide-plate is preferably formed with ridges 61 adjacent to the edge-gages to assist in keeping the stock in contact therewith. The guide-plate is slidably secured to a plate 62 having a fixed position on the machine, this movement being permitted by securing it by means of bolts passing through the slot 64 in the shank of the guide-plate and holes 66 in the plate 62. It will thus be seen that the guide-plate unless restrained is free to slide back and forth into the two extreme positions shown in Figs. 1 and 5 although normally drawn into rearward position in the manner now to be described. The extreme rear end 67 of the guide-plate is connected by a spring 68 to a fixed part of the machine and therefore the guide-plate carrying with it the edge-gages 60 is pulled in the direction of the arrow *z* and assumes the position shown in Fig. 1 except when held out of this position against the tension of the spring 68 by the means now to be described.

The plate 62 has an integral extension provided with a ratchet 70 whose teeth are inclined forwardly as shown in Figs. 2 and 6. A pawl 72 is pivoted on a pin 74 extending between lugs 76 on the block 50. The pawl is held by the means now to be described in the position shown in Fig. 2 so that it is out of engagement with the ratchet when no stock is inserted. Pivoted on the pin 74 independently of the pawl is a lever 80 which at one end is engaged by a lip 82 formed by bending over the end of the leaf-spring which carries the presser-foot. The pawl 72 carries a pin 84 projecting laterally on both sides thereof. Upon one side said pin serves as a means for securing one end of a spring 78 while upon the other side said pin overlies the upper surface of the lever 80 at the end of said lever opposite that engaged by the lip 82. The lever 80 therefore is so arranged that it holds the pawl 72 out of engagement with the ratchet 70 against the tension of the spring 78, as shown in Fig. 2, when no stock is inserted. When, however, stock is inserted, as shown in Fig. 6, the spring presser-foot 54 is raised, the lever 80 is rocked, thus lowering the end which is engaged by the pin 84 and permitting the spring 78 to force the

pawl into engagement with the ratchet. The stock is inserted when the mechanism occupies the position shown in Fig. 1. At this time the guide-plate is drawn to its extreme rearward position by the spring 68. The edge-gages 60 on the block 50 are thus in extreme rearward position relatively to the anvil-plate and the first eyelet will be set somewhat remotely from the edge of the upper, as shown in Fig. 5. After this eyelet has been set the lever 18 is rocked in the direction of the arrow x , Fig. 5. Through the links 14 and 16 the anvil-plate 2 is turned on its pivot 4 to move the setting-dies 12 the distance between successive eyelets, and these dies being still in engagement with the stock, feed the same the required distance. At the same time the links 26 and 28 are moved into the position shown in Fig. 5 and the stud 30, secured to the link 28, is partially rotated. The plate 34 and finger 36 are turned and the end of the finger by engaging with the lug 48 forces the guide-plate in the direction of the arrow y to its forward position.

Since the teeth on the stationary ratchet 70 are inclined forwardly the pawl 72 moves thereover and when the guide-plate has been moved into its forward position it is held there by the engagement of the pawl with the teeth until the remaining eyelets have been set in the shoe upper and the latter has been removed. Upon removal of the upper, the presser-foot 54, lever 80 and pawl 72 again assume the position shown in Fig. 2 and the spring 68 draws the guide-plate 49 and attached edge-gages 60 to rearward position to give the desired spread to the first eyelet on the next shoe-upper.

It is sometimes desirable to dispense with the spread of the first eyelet and set all of the eyelets at the same distance from the edge of the shoe-upper. The following device is provided for this purpose. Upon the guide-plate 49 is a ratchet having rearwardly inclined teeth 86 while upon the stationary plate 62 is mounted a casing 88 carrying a spring-pressed plunger 90. The end of this plunger is made in the form of a ratchet 92.

The plunger is provided with a head 94 and a pin 96, the latter being adapted to fit into a notch 98 in the casing. With the parts in the position shown in Fig. 3 it will be seen that the plunger is held in position to have its end or pawl-like portion 92 in engagement with the teeth 86, and the guide-plate 49 is therefore held in forward position against the tension of the spring 68 and any change in the spread of the eyelets is thus prevented.

When, however, the plunger is drawn backward and turned so that the pin 96 is prevented from entering the notch 98, as shown in Fig. 7, the spread of the eyelets is varied as previously stated.

It will be noted that the edge-gages 60 are inclined at an angle on the side from which

the stock is fed. By presenting the stock to the machine with its edges parallel to the inclined edges of the gages the distance of the holes punched in the stock and of the eyelets set therein from the edges of the stock is diminished while by turning the stock into the position shown in Fig. 1 this distance may be increased. This feature constitutes no part of the present invention, but in connection with the means for automatically varying the position of the edge-gages affords a convenient means for varying the position of the first few eyelets set in the bottom of the flaps of the shoe-upper.

The operation of the machine will be understood readily from the foregoing description. The operator inserts the two flaps of the shoe-upper between the guide-plate and the two presser-feet respectively and starts the machine. The punches come in contact with the punching-blocks 10 from opposite sides and a hole is punched in the lower portion of each flap. The lever 6 is then actuated and the anvil-plate 2 is moved rearwardly to bring the setting-dies 12 into the position previously occupied by the punching-blocks. Setting devices then coöperate with the setting-dies 12 to set the first eyelets. The edge-gages during this time occupy their rearward position and the first eyelet in each flap is set somewhat remote from the edges of the lacing-slit. The lever 18 then moves in the direction of the arrow x , Fig. 5, to feed the work one space and to move the guide-plate forward in the direction of the arrow y . The anvil-plate then returns to initial or punching position and since the edge-gages have been moved forwardly relatively to the anvil-plate it is evident that the holes will now be punched nearer to the lacing-slit than before. The remaining eyelets in the series are then set consecutively and upon removal of the shoe-upper from the machine the guide-plate and edge-gages are returned automatically to initial position, whereupon the cycle of operations may be repeated.

Having described my invention, what I claim as new and desire to secure by Letters Patent of the United States is:—

115

1. In an eyeleting machine, the combination with a guide-plate, of means located on opposite sides thereof for determining the position of the work relative to said guide-plate, and means for automatically changing the position of said first mentioned means to vary the spread of the eyelets.

2. In an eyeleting machine, the combination with a guide-plate, of means located on opposite sides thereof for determining the position of the stock relative to said guide-plate, and means for automatically changing the position of said first mentioned means after the first eyelet in a series has been set.

3. In an eyeleting machine, the combina-

130

- tion with a guide-plate, of means for determining the position of stock relative to said guide-plate, means for automatically changing the position of said first mentioned means to vary the spread of the eyelets, and means for preventing change in the position of said first mentioned means when a uniform spread is desired.
4. In an eyeleting machine, the combination with a guide-plate, of edge-gages on opposite sides thereof, and means for automatically changing the position of said edge-gages to vary the spread of the eyelets.
5. In an eyeleting machine, the combination with a guide-plate, of edge-gages secured on opposite sides thereof, and means for automatically changing the position of said edge-gages and guide-plate to vary the spread of the eyelets.
6. In an eyeleting machine, the combination with a guide-plate, of edge-gages on opposite sides thereof, and means for automatically changing the position of said edge-gages after the first eyelet in a series has been set.
7. In an eyeleting machine, the combination with an edge-gage, of means for automatically changing the position of said edge-gage to vary the spread of the eyelets, and means for preventing change in the position of said edge-gage when a uniform spread is desired.
8. In an eyeleting machine, the combination with a guide-plate, of an edge-gage, an anvil-plate, and means for automatically changing the relative position of said edge-gage and said anvil-plate to vary the spread of the eyelets.
9. In an eyeleting machine, the combination with an edge-gage, of means for maintaining said edge-gage in one position until the first eyelet in a series has been set, means for then automatically moving said edge-gage into another position, and means for maintaining said edge-gage in the latter position while the remaining eyelets in the series are set.
10. In an eyeleting machine, the combination with a guide-plate, of an edge-gage thereon, a presser-foot yieldingly mounted on said guide-plate, means for automatically changing the position of said edge-gage, and

means actuated by said presser-foot for maintaining said edge-gage in changed position.

55

11. In an eyeleting machine, the combination with a guide-plate, of an edge-gage thereon, a presser-foot yieldingly mounted on said guide-plate, a stationary member to which said guide-plate is slidably secured, means for normally holding said guide-plate in rearward position, means for moving said guide-plate forwardly, and means for maintaining said edge-gage, in forward position until the stock is removed from the machine.

60

12. In an eyeleting machine, the combination with a guide-plate, of an edge-gage thereon, a presser-foot yieldingly mounted on said guide-plate, a stationary member to which said guide-plate is slidably secured, means for normally holding said guide-plate in rearward position, means for moving said guide-plate forwardly, a lever having one end held in engagement with said presser-foot, a ratchet, a pawl on said guide-plate normally held out of engagement with said ratchet by the other end of said lever, and means for causing said pawl to engage with said ratchet when said presser-foot is moved away from said guide-plate.

70

13. In an eyeleting machine, the combination with a guide-plate, of edge-gages thereon, presser-feet yieldingly mounted on opposite sides of said guide-plate, a stationary member to which said guide-plate is slidably secured, a ratchet secured to said stationary member, a spring for normally holding said guide-plate in rearward position, an oscillating finger, a lug on said guide-plate arranged to be engaged by said finger, a lever having one end held in engagement with one of said presser-feet, a pawl on said guide-plate normally held out of engagement with said ratchet by the other end of said lever, and a spring for forcing said pawl into engagement with said ratchet when said presser-foot is moved away from said guide-plate.
